Primary Examiner — Melanie H Tung(74) *Attorney, Agent, or Firm* — Banner & Witcoff, Ltd.**CLAIM**

The ornamental design for a display screen with graphical user interface, as shown and described.

DESCRIPTION

The FIGURE is a front view of a display screen with a graphical user interface showing the new design.

The broken line showing of the display screen is for environmental purposes only and forms no part of the claimed design.

1 Claim, 1 Drawing Sheet(56)
